UNITED STATES PATENT OFFICE.

NELSON STURDEVANT, OF DETROIT, MICHIGAN.

WIND-SHIELD JOINT.

1,107,863.

Specification of Letters Patent. Patented Aug. 18, 1914.

Application filed May 29, 1913. Serial No. 770,587.

To all whom it may concern:

Be it known that I, NELSON STURDEVANT, a citizen of the United States of America, residing at Detroit, in the county of Wayne 5 and State of Michigan, have invented certain new and useful Improvements in Wind-Shield Joints, of which the following is a specification, reference being had therein to the accompanying drawings.

10 This invention relates to a hinge or pivot joint and to an arrangement thereof that adapts it particularly for use in wind shields and like places where it is desired to hold a sash member or the like in adjusted angular 15 relation to another member by means which are easily operable and which are so disposed as not to obstruct the vision.

The invention consists in the matters hereinafter set forth, and more particularly 20 pointed out in the appended claims.

In the drawings, Figure 1 is a view of an assembled joint, partially broken away and partially in section, that embodies features of the invention; Fig. 2 is a view, partially 25 in longitudinal section and partially in side elevation, of the joint with the parts free for adjustment; Fig. 3 is a view, partially in section and partially in elevation, taken at right angles to Fig. 2; Fig. 4 is a view in detail showing the position of the parts when 30 locked; and Fig. 5 is a view in detail of a keeper; Fig. 6 is a view in detail showing a modification of the invention; Figs. 7 and 8 are views in detail of an operating lever in 35 a modification; and Fig. 9 is a view in detail of another form of the operating lever.

As herein shown in preferred form a sash member 1 has a circular bearing plate 2 that is formed integral on or secured to the end 40 portion of the latter as a bearing member. A flanged or other rabbeted margin indicated at 3 corresponds to the flange and rabbeted margin 4 of a circular cap 5 that is secured, as by a tongue 6 and screws 7 in 45 spaced and non-rotatable engagement with the plate. The sash member 8 has a bearing hub 9 formed or secured on the end thereof to swing on the rabbeted margins of the cap and plate. The interior periphery of the 50 hub has a plurality of flutes 10 or recesses. As a matter of good construction these may be formed in a bushing 11 of hardened metal that is inset in the hub and non-rotatably secured thereto as by pins 12 or other suitable 55 means.

A pair of oppositely disposed keepers 13

or blocks have sliding engagement in a transverse slot or guide-way in the tongue 6 of the cap, being yieldingly separated or projected by a suitably disposed spring 14 or 60 the like so that they bear against the fluted or recessed face of the hub or bushing. Preferably the flutes 10 are semi-cylindrical depressions to conform to a roll 15 that is inset in a suitable guide socket 16 of each 65 keeper so as to turn freely and eliminate rubbing contact with the hub.

A locking stud 17 is in screwthreaded engagement with an opening through the cap transverse to the slot in which the keepers 70 play, preferably at the axial center of the cap and hub. A circular head 18 on the inner end of the stud, is proportioned to enter between the keepers 13 when the latter are fully projected with the rolls in engagement 75 with opposite recesses of the hub and thereby lock them in such position. The outer head 20 of the stud is arranged for convenient manipulation and is so disposed that when seated against the cap 5, the inner 80 head is in locking position while a partial turn of the stud in reverse withdraws the inner head into a recess or counterbore of the cap, as indicated in Fig. 2, to clear the keepers. 85

In the modifications shown in Figs. 6 to 9 inclusive oppositely disposed locking bars 21 are provided in the sash bar 22 of a wind shield or the like with inwardly projecting stems 23. A latch handle 24 at the middle 90 of the bar, as indicated in Figs. 7 and 8, has a cam plate 26 that is adapted to force the stems 23 apart and thereby push the members 21 between the blocks 13 when the latter are separated by the action of the 95 spring 14, thus maintaining the hinges in locked relation. In this construction suitably disposed springs 27 withdraw the members 21 when the latch 24 is in initial position. Or, as indicated in Fig. 9, the 100 inner end portions 28 of the stems 23 may have pins 29 engaging eccentric slots 30 of a latch member 31 whereby oscillation of the latter positively moves the stems both inwardly and outwardly. Any suitable 105 connection between a central lever and the members 21, may, of course, be substituted for those indicated so that by a single movement of the lever both sides of the window shield or sash may be simultaneously locked 110 fast.

When assembled, the hub members may

be swung on the other members into the angle desired and the parts may then be locked in position either by turning one or both of the studs inwardly to seat, or in 5 the modified form by forcing the other locking members between the keepers by use of the latch.

The modification allows the user to operate a wind shield, for example, from 10 either side of a car or from the driver's seat as preferred.

The joint is positive in operation, is simple in construction and presents an exterior 15 that does not obstruct the vision when used in combination with an automobile wind shield or the like. As the bearing face of the hub and the friction rolls of the keepers may be made of hardened material the parts 20 do not wear appreciably under long and severe usage.

Obviously, changes in the details of construction may be made without departing 25 from the spirit of my invention and I do not care to limit myself to any particular form or arrangement of parts.

What I claim is:—

1. A pivot joint comprising a member having a hub with recesses in the inner periphery thereof, a member having a bearing plate on which the hub is journaled, a cap secured to the plate and adapted to hold the hub thereon, a pair of oppositely disposed yieldingly projected keepers movable in the cap in the plane of rotation of 30 the hub adapted to engage the hub recesses, and a locking member in the cap movable transversely of the keepers and having a rotatable head for holding them separated and interlocked positively with the hub, the head of said member receding into said cap to provide clearance for said keepers.

2. A pivot joint comprising a member having a hub with a series of recesses in the inner periphery thereof, a member having 45 a bearing plate, a cap non-rotatably secured to the plate, the hub being journaled on the cap and plate, a pair of oppositely disposed keepers movable in a transverse guideway in the cap adapted to enter the recesses in 50 the hub, a spring between said keepers and a locking member in the cap adapted to be forced between the proximate ends of the keepers in proximity to said spring when the latter have entered recesses in the 55 hub and to hold them in such position.

3. A pivot joint comprising a member having a hub, a bushing secured in the hub with recesses in the inner periphery thereof,

a member having a bearing plate on which the hub is rotatable, a cap non-rotatably secured to the plate and adapted to co-act with the latter as a bearing for the hub, oppositely disposed keepers in sliding engagement with the cap adapted to enter the bushing recesses, a compression spring arranged between said keepers and having end convolutions engaging said keepers, and a locking member in the cap adapted to be forced between the proximate ends of the keepers at one side of said spring 70 when the latter have entered opposite recesses for securing them therein.

4. A pivot joint comprising a member having a hub with longitudinally fluted inner periphery, a bearing plate having a rabbeted margin on which the hub is rotatable, a cap non-rotatably secured to the plate and having a rabbeted margin and adapted to hold the hub thereon, a pair of oppositely disposed keepers movable in a 80 transverse guideway in the cap, a friction roll journaled in the end of each keeper and adapted to enter the flutes of the hub, a spring arranged between said keepers and a locking member in the cap adapted 85 to be forced between the proximate ends of the keepers at one side of said spring when the rolls have entered opposite recesses in the hub and to lock the keepers in such position.

5. A pivot joint comprising a member having a hub, a member having a plate on which the hub is journaled, a cap non-rotatably secured on the plate for retaining the hub thereon provided with a transverse 95 guideway, a bushing non-rotatably secured to the hub between the plate and cap and provided with a fluted interior periphery, a pair of keepers sliding in the guideway, a spring member yieldingly projecting the 100 keepers, a friction roll journaled in the outer end of each keeper and adapted to enter the flutes of the bushing, and a stud in screw-threaded engagement with the cap having an inner head adapted to lie between the keepers at one side of said spring 105 when the rolls of the latter are in opposite recesses and the stud is screwed home in the cap.

In testimony whereof I affix my signature 110 in presence of two witnesses.

NELSON STURDEVANT.
